United States Patent Office

Des. 206,400
Patented Dec. 6, 1966

206,400

DISPENSER

Theodore L. Williams, 10201 Tracy,
Kansas City, Mo. 64155

Filed July 22, 1965, Ser. No. 86,257

Term of patent 14 years

(Cl. D52—3)

Fig.2.

Fig.1.

Fig.4.

Fig.3.

FIG. 2 is a side elevational view thereof;

FIG. 3 is a top plan view thereof; and

FIG. 4 is a rear elevational view of the dispenser.

The undisclosed side of the dispenser is substantially the same in appearance as the side shown.

I claim:

The ornamental design for a dispenser, as shown and described.
